UNITED STATES PATENT OFFICE.

HENRY C. SERGEANT, OF CINCINNATI, OHIO.

IMPROVEMENT IN GAS-REGULATORS.

Specification forming part of Letters Patent No. 34,985, dated April 15, 1862.

To all whom it may concern:

Be it known that I, HENRY C. SERGEANT, of Cincinnati, in the county of Hamilton and the State of Ohio, have invented a new and Improved Regulator for Gas; and I do hereby declare that the following is a full, clear, and exact description of the same, reference being had to the accompanying drawings, making part of this specification, in which—

Figure 1 is a perspective view. Fig. 2 is a vertical part section of the key of gas-cock, showing the regulating-screw. Fig. 3 represents the nut for holding the key in its place. Fig. 4 represents the regulating-screw for increasing or diminishing the opening in the key of the cock.

My improved regulator consists in the arrangement of a small screw placed in one end of the key of the cock, so arranged that by turning it the opening in the key can be increased or diminished at pleasure, according to the amount of light required, the stop-cock being used for turning on and off the gas and the regulating-screw to govern the amount of opening.

To enable those skilled in the art to make and use my invention, I will proceed to describe its construction and operation.

Similar letters of reference indicate corresponding parts in the several figures.

A represents the regulating-screw, which is to be adjusted to the desired amount of open-

ing, (by a key or wrench made for that purpose.)

B represents the lock-nut, which is also adjusted by the wrench to hold the key of the cock in its proper position.

C represents the opening in the key of the cock, which is increased or diminished by the turning of the regulating-screw.

The operation is easily understood. Open the gas-cock with the thumb and finger, then place the wrench upon the regulating-screw, turn it until you have the desired amount of light, then set the lock-nut down to its proper place, allowing the key of the cock to move freely. Then by opening and shutting the gas-cock you will find that you always have the same amount of light, and the amount of opening by this arrangement can easily be adjusted by the consumer, so as to prevent servant-girls, children, and others from wasting gas.

What I claim as my invention, and desire to secure by Letters Patent, is—

The application of an adjustable screw placed in one end of the key of a gas-cock, so arranged as to control the amount of opening in the key, as specified in the foregoing specification.

HENRY C. SERGEANT.
